(57) **CLAIM**

The ornamental design for a cart, as shown and described.

DESCRIPTION

FIG. 1 is a rear perspective view of a preferred embodiment of a cart with a pair of cylinder tanks, a handle, a pair of wheels and various control devices shown in broken lines; FIG. 2 is a right side elevated view of the cart shown in FIG. 1, with the left side view being a mirror image thereof; FIG. 3 is a front elevated view of the cart shown in FIG. 1; FIG. 4 is a top plan view of the cart shown in FIG. 1; FIG. 5 is a rear elevated view of the cart shown in FIG. 1; and, FIG. 6 is a bottom plan view of the cart shown in FIG. 1. The broken lines showing the wheels, tanks, straps, handle and control devices, or portions thereof, in FIGS. 1-6 are for illustrative or environmental purposes only and do not form any part of the claimed design.
